UNITED STATES PATENT OFFICE.

CARL E. BROWN, OF COLUMBUS, OHIO.

OIL-BURNER.

1,184,616.

Specification of Letters Patent.

Patented May 23, 1916.

Application filed March 24, 1915. Serial No. 16,712.

To all whom it may concern:

Be it known that I, CARL E. BROWN, a citizen of the United States, residing at Columbus, in the county of Franklin and State of Ohio, have invented a new and useful Oil-Burner, of which the following is a specification.

The device forming the subject matter of this application is a burner of that general type in which the upper arm of a U-shaped oil supply pipe is heated from a combustion orifice in the lower arm of the pipe, thereby to convert the oil in the upper arm of the pipe into gas which burns at the combustion orifice in the lower arm of the pipe. In order that the oil or other liquid fuel may be vaporized in the upper arm of the pipe, it is necessary that the upper arm be heated to a comparatively high degree. When the burner is started in operation, the upper arm of the pipe, of course, is not heated. It has been proposed hitherto to mount the U-shaped pipe slidably and to arrange adjacent the lower arm of the pipe a tray which is adapted to receive oil or fuel from the lower arm of the pipe, the pipe being slid endwise so that the combustion orifice may discharge a quantity of oil or fuel onto the tray. The pipe is then returned to its original position, and the oil or fuel in the tray is lighted, thus to heat the upper arm of the pipe and to vaporize the fuel therein at the starting of the burner.

The construction above described presupposes that the arched or U-shaped pipe is free to slide in the direction of its length and one of the disadvantages attendant upon the above mentioned operation is that if the pipe is to slide longitudinally, sufficient room must be provided so that the sliding operation in question may take place.

The present invention contemplates that the arched or U-shaped pipe shall be fixedly mounted against longitudinal movement, a novel means being provided whereby at the starting of the burner, the fuel in the U-shaped pipe may be carried onto the tray, to be lighted for the purpose of heating the upper or vaporizing arm of the pipe.

The invention aims to improve structurally and in detail, as well as to present broadly, a means whereby the step last above mentioned may be carried out.

With the above and other objects in view which will appear as the description proceeds, the invention resides in the combina-

tion and arrangement of parts and in the details of construction hereinabove described and claimed, it being understood that changes in the precise embodiment of the invention herein disclosed can be made within the scope of what is claimed, without departing from the spirit of the invention.

In the accompanying drawings: Figure 1 shows the invention in side elevation, parts being broken away; Fig. 2 is a top plan whereby the supply and vaporizing pipe has been omitted; Fig. 3 is a cross section taken approximately on the line 3-3 of Fig. 1. Fig. 4 is an elevation of the supporting bracket.

The structure forming the subject matter of this application preferably is fashioned from metal throughout saving as hereinabove specifically modified, and comprises a box like casing 1 including a lid 2 which may be removable. At its ends, the lid 2 is provided with upstanding pyramidal combustion chambers 3, open at their lower ends so as to communicate with the interior of the casing 1, the smaller, upper ends of the combustion chambers 3 terminating in outlets 4. The construction, therefore, is such that air may draw upwardly through the casing 1 and through the outlets 4 of the combustion chambers. The combustion chambers 3 are provided with openings 5 and below the openings 5, in the adjacent or inner faces of the combustion chambers, elongated slots 6 are formed. Between the combustion chambers 3 and along its edges the lid 2 is equipped with upstanding flanges 7 defining a tray which may be filled with a layer of ashes, with asbestos, or with any other suitable absorbent material, denoted by the numeral 8.

The invention contemplates the use of a U-shaped or arched pipe 9 comprising an upper arm 10 and a lower arm 11. The upper arm 10 of the pipe 9 lies above the outlets 4 of the combustion chambers 3, the lower arm 11 passing through the openings 5 in the combustion chambers, the arms of the pipe 9 being united by a bend 12 and the extremity of the lower arm 11 being closed by a cap 14 or in any other suitable manner. The lower arm 11 of the pipe 9 is provided with combustion orifices 16 lying within the contour of the chambers 3 and preferably disposed coaxially with respect to the openings or outlets 4. The pipe 9 is supported by means of a bracket 15 preferably

of arched construction, the bracket being secured to the lid 2 and supporting the upper arm 10 of the pipe 9. Flame spreaders 17 are attached to the upper arm 10 of the pipe 9 and lie above the outlets 4 of the combustion chambers 3. At this point it may be noted that heretofore, in order to apply a priming charge to the tray, the pipe 9 has been slid longitudinally, thereby to dispose 5 one of the combustion orifices 16 outside of the corresponding combustion chamber 3, to the end that oil or fuel may run out onto the tray, the pipe 9 being restored to its original position and the oil in the tray being ignited beneath the upper arm 10 of the pipe at the starting of the burner. This operation is disadvantageous. If the pipe 9 is to be slid in the direction of the arrow A in order to dispose one of the combustion 10 orifices 16 outside of the corresponding chamber 3, the bend 12 must extend to the left a considerable distance beyond the showing in Fig. 1. If the pipe 9 is to be slid in the direction of the arrow B in carrying out the operation above mentioned or, indeed, if the pipe is to be slid either in the direction of the arrow B or in the direction of the arrow A, a space must exist 15 at each end of the casing 1 to permit such a sliding movement. To render the burner compact and to render it unnecessary to provide a space for the sliding movement of the pipe 9 is one of the objects of this invention.

30 In order that fuel may be discharged into the tray without shifting the pipe 9 endwise, a pair of discharge members are located partly within the combustion chambers 3 and lie beneath the orifices 16. The discharge members 18 comprise side walls 19 and a rear wall 20, the forward or inner ends of the discharge members being open. The discharge members slant downwardly toward each other and pass through the 35 slots 6 in the walls of the chambers 3, the inner or adjacent ends of the discharge members being secured to the lid 2 within the contour of the tray by means of attaching elements 21. The outer ends of the discharge members 18 may bear against the under edge of the lower arm 11 of the pipe. It will now be understood that when it is 40 desired to deposit a priming charge in the tray, a quantity of oil or fuel is permitted

to run out of the orifices 16, the oil flowing onto the discharge members 18 and passing therefrom onto the absorbent material in the tray. Owing to the fact that two discharge members 18 are provided, the fuel is distributed fairly and evenly over the 45 tray. It is to be observed, further, referring particularly to Fig. 2 that the discharge members 18 extend beyond the periphery of the outlets 4 and therefore serve as baffles tending to distribute evenly around the combustion chambers, the air which passes upwardly therethrough. Another advantage in having the U-shaped pipe stationary is that permanent plumbing may be used on the outside of the stove, leading 50 from the burner to an oil tank, whereas, if the U-shaped pipe is slideable, a flexible tubing must be resorted to.

Having thus described the invention, what is claimed is:—

75 In a device of the class described, a tray; a tapered combustion chamber carried by the tray, the chamber having an outlet in its top and being provided upon the side adjacent the center of the tray with a slot located close to the bottom of the tray; an arched pipe extended longitudinally of the tray and embodying an upper arm located above the outlet and a lower arm passing through the combustion chamber above the 80 slot, the lower arm having a combustion orifice disposed within the chamber; and a pan located partly in the chamber and extended outwardly through the slot, the pan being secured to the tray exteriorly of the 85 chamber and lying below the orifice in the lower arm of the pipe, the pan being inclined longitudinally of the tray from the central portion of the tray toward the outer end thereof for the double purpose of deflecting into the tray fuel discharged into the pan through the orifice and of deflecting away from the slot, air rising through the chamber, the pan being of a greater 90 area than the outlet.

95 In testimony that I claim the foregoing as my own, I have hereto affixed my signature in the presence of two witnesses.

100 CARL E. BROWN.
